UNITED STATES PATENT OFFICE

JAMES ELBERT WARD, OF ROCKFORD, MICHIGAN

STONE GATHERER

Application filed September 29, 1930. Serial No. 485,185.

An object of the present invention is the provision of a machine for simultaneously gathering stones, removing dirt and trash therefrom, and loading them into a box from which they are dumped as desired.

5 A further object of the invention is the provision of a machine of the character aforesaid which is adapted to be readily steered and adjusted, and which embodies few parts.

10 While the drawings illustrate a preferred embodiment of the invention, it is to be understood that in adapting the means to meet specific needs and requirements the design may be varied and changes in the minor details of construction may be resorted to within the scope of the invention as claimed, without departing from the spirit thereof.

20 For a full understanding of the invention and the merits thereof, reference is to be had to the following description and the drawings hereto attached, in which:

Figure 1 is a top plan view of a stone gatherer embodying the invention.

Figure 2 is a side view partly in section, on the line 2—2 of Figure 1, and having a portion of the box for receiving the stones, broken away.

30 Figure 3 is an enlarged sectional view on the line 3—3 of Figure 2, looking toward the front, as indicated by the arrows.

Figure 4 is a detail horizontal sectional view on the line 4—4 of Figure 3.

35 Corresponding and like parts are referred to in the following description and designated in the several views of the drawings by like reference characters.

The main frame comprises longitudinal side bars 1, a rear cross bar 2, and a front transverse member 3. A rear axle 4 is mounted on the rear portion of the frame and receives wheels 5 which also act as drivers. Front wheels 6 are pivotally mounted for convenience of steering.

40 Standards 7 are mounted in the transverse member 3 for vertical adjustment and their lower ends pivotally support the wheels 6. Levers 8 are pivoted intermediate their ends as at 80, to the transverse member 3 and their outer ends are pivotally and slidably connected to the upper ends of the standards 7

by pin and slot connections 81. The inner ends of the levers 8 are pivotally and slidably connected by pin and slot connections 82 to a block 9 which is adjustable vertically. A vertically disposed adjusting screw 10 is mounted in a block 11 carried by the transverse member 3 and its lower end is connected to the block 9 by means of a swivel joint. Rotation of the adjusting screw 10 elevates or lowers the block 9 and effects a corresponding adjustment of the standards 7 through the levers 8. In this manner, the front end of the main frame is adapted to be raised or lowered.

45 The wheels 6 are mounted upon spindles 12 which are pivotally connected to the lower ends of the standards 7 and from which arms 13 project forwardly. Links 14 connect the forward ends of the arms 13 to a tongue 15 pivoted at its rear end to a bracket 16 depending from the transverse member 3. Lateral movement of the forward end of the tongue 15 effects angular adjustment of the wheels 6 whereby the machine may be steered as required. The draft may be hitched to the tongue 15 and may consist of a tractor or horses, as found most advantageous.

50 Brackets 17 depend from the forward portion of the main frame. Uprights 18 rise from the rear portion of the main frame. A transverse shaft 19 is mounted in the uprights 18 and receives sprocket wheels 20. A transverse shaft 21 is mounted in the brackets 17 and receives sprocket wheels 22. An endless conveyor is mounted upon the sprocket wheels 20 and 22 and comprises chains 23 and lags 24. The lower run of the endless conveyor travels upwardly and rearwardly over a grid 25 which inclines upwardly and rearwardly and which is connected at its lower forward end to the brackets 17 and at its upper rear end to the main frame. A box 26 at the rear end of the machine receives the stones as they are discharged from the upper rear end of the grid 25. Drive chains 27 connect gear wheels 28 on the axle 4 with gear wheels 29 fast to the transverse shaft 19, whereby the endless conveyor is driven, as the machine is drawn or otherwise propelled over the ground. Skipper levers 30

are provided as convenient means for throwing the endless conveyor into and out of gear by connecting the sprocket wheels 28 with the wheels 5 or disengaging them therefrom.

- 5 The lower end of the grid 25 trails upon the ground and the stones in the path thereof are swept onto and over the grid by means of the endless conveyor. Any dirt or trash 10 drops through the spaces formed between the bars comprising the grid 25. The upper end of the grid 25 terminates above the box 26 so that the stones dropping from the grid are received in the box 26. A trap door 31 in the bottom of the box 26 provides for convenient and ready discharge of the stones when required. The forward end of the stone 15 gathering mechanism, including the grid 25 and endless conveyor, may be adjusted vertically through the instrumentality of the adjusting screw 10, levers 8, standards 7, and wheels 6, as will be readily appreciated.

When the machine is propelled over the ground and the sprocket wheels 28 are in 20 clutched engagement with the wheels 5, the endless conveyor is set in motion and sweeps the stones onto and over the grid 25, from which they drop into the box 26 to be discharged therefrom as required.

25 What is claimed is:

30 The combination of a main frame, vertically adjustable standards at the front end of the frame, an adjusting screw mounted vertically in the front end of the frame, levers fulcrumed between their ends on the 35 frame and having their inner ends operatively connected with the lower end of the screw and their outer ends operatively connected with the upper ends of the standards, front wheels pivotally connected to the lower 40 ends of the standards, a bracket depending from the frame, a tongue pivoted at its rear end to said bracket, and links forming connecting means between the tongue and front wheel mountings.

45 In testimony whereof I affix my signature.
JAMES ELBERT WARD. [L. S.]
